UNITED STATES PATENT OFFICE.

ADOLPHE PAROUTAUD, OF NEW YORK, N. Y.

DESIGN FOR A COVERED DISH.

SPECIFICATION forming part of Design No. 29,788, dated December 13, 1898.

Application filed November 19, 1898. Serial No. 696,945. Term of patent 3½ years.

To all whom it may concern:

Be it known that I, ADOLPHE PAROUTAUD, of the city of New York, borough of Manhattan, in the county and State of New York, 5 have invented and produced a new and original Design for a Covered Dish, of which the following is a specification, reference being had to the accompanying drawings, forming a part thereof, in which—

10 Figure 1 is a plan view of a dish embodying the features of my design, and Fig. 2 is a side elevation of the dish.

The body A of the dish is given a depression *a* near its base B, producing between the 15 base and said depressed surface a horizontal ridge *b*, and the exterior surface of the body between the ridge *b* and the top edge of said body is given an outward swell C. The swell portion of the body between its ends is di-

vided into panels, sundry of which have a 20 fluted effect. A fluted appearance is also given to the base portion of the body.

The minor features of the design consist in ribbon-like handles for the body and the cover D and in corresponding marginal decorations for the cover and body, said decorations combining a stippled ground and raised ornamental figures. The cover is further decorated with a drapery-figure around and below its handle. 25

I claim—

The design for a covered dish herein shown and described.

ADOLPHE PAROUTAUD.
